SUPPORTING DEVICE FOR LAMPS

Filed July 12, 1929

Inventor:
Roy B. Miner
by Charles E. Tullar
His Attorney

UNITED STATES PATENT OFFICE

ROY B. MINER, OF NAHANT, MASSACHUSETTS, ASSIGNOR TO GENERAL ELECTRIC COMPANY, A CORPORATION OF NEW YORK

SUPPORTING DEVICE FOR LAMPS

Application filed July 12, 1929. Serial No. 277,814.

My invention relates to supporting devices for electric lamps. More particularly it relates to devices of this character especially adapted for use in connection with light projectors such as flood lighting devices and the like.

In devices of the kind specified it is especially desirable to have the light source supported by means capable of being readily adjusted from the rear of the casing not only with respect to a point as a center but radially with respect to said center and readily clamped in the adjusted position from the rear of the device, and therefore it is an object of the invention to provide means for accomplishing the foregoing.

The following specification describes the invention in detail, reference being had to the accompanying drawings in which Fig. 1 shows a flood lighting device provided with the features of the invention. In this figure the flood light is shown in elevation and partly in section. Fig. 2 shows an enlarged view of the supporting means in elevation and partly in section.

Referring in detail to the drawings it will be seen that the flood light comprises the usual base 2, casing 3, and lens 4, the latter being secured to the front of the device. Within the casing there is located the usual reflector 5, which latter is secured to the casing in any suitable manner. The reflector is perforated at the rear along the axis, thereby enabling the light source to be supported in front of the reflector through means secured to the casing behind the reflector and in the focal region of the reflector. The supporting device for the light source comprises a lamp socket 6, a holder 7, a collet 8, a collar 9, a ball 10, a socket in the form of a cap 11, a bar nut 12, a shaft 13 and a knob 14. The collet comprises a sleeve provided with a head at one end and a threaded portion at the other end and operates as a bearing for the shaft 13, enabling the shaft to be rotated on its own axis, and enabling the shaft to be slid longitudinally along its own axis. As shown in the drawing the section 16 of the casing around the longitudinal axis is spherical,

the inner surface being concave and the outer surface being convex. The concave side serves as a seat for the ball 10 and the convex side serves as a seat for the cap or socket 11. As shown in Fig. 2 the cap 11, the bar nut 12 and the knob 14 are located on one side of the casing, while the lamp socket 6, the holder 7, the collar 9 and the ball 10 are on the opposite side, that is, on the inside of the casing. It will be seen that the shaft 13 extends through the nut 12, the cap 11, spherical section 16 of the casing, ball 10 and collar 9, and has secured to its inner end the holder 7, as for example, by means of a cotter pin 18. On the outer end of the shaft is secured a knob 14, by means of a set screw 17. The collet as shown is threaded at the rear end and the bar nut is also threaded to receive the threaded portion of the collet. The collet on its inner end is slotted as indicated by the slot 15. The collar 9 is centrally perforated and the perforation is tapered to receive the tapered neck of the collet as shown. Furthermore, the collar 9 fits over the ball 10 as indicated. While the collar and ball are shown as two separate pieces they may be formed as a unit perforated to receive the collet 8. It will be seen that by turning the nut 12 in one direction the collar 9 and the ball 10 are drawn by the collet toward socket 11, clamping the spherical section 16 of the casing between them. This is one function of the collet. The same operation obviously compresses the section of the collet on the opposite sides of the slot 15, thus clamping the shaft in any adjusted position with respect to the collet and therefore with respect to the casing and with respect to the reflector. This is the second function of the collet. That is, it not only locks the shaft against longitudinal or rotary motion with respect to its own axis, but it also locks the ball 10 against rotation about its center and consequently locks the shaft against rotation about the same center.

If an adjustment of the light source is desired the nut 12 is turned in the opposite direction, thereby releasing the collet and

consequently releasing the elements previously clamped. It is then possible by moving the shaft longitudinally or by rotating it about its longitudinal axis or by rotating the ball 10 through the medium of the shaft and its knob 14, or by performing all of these operations, to adjust the filament of the light source in any position about the focal point of the reflector 5, in which position the light source may be readily locked by turning the nut 12 in the opposite direction thus clamping the shaft to the collet, the collet to the ball and socket and the ball and socket to the casing.

15 As shown in the drawing, current may be conveyed to the lamp by means of conductors 19, which pass through any suitable opening in the casing and which may be carried thereto, for example, in a cable 20, 20 there being suitable clamping and sealing means 21 around the cable to prevent the entrance of foreign matter into the casing.

While I have shown in the drawing one form of my invention, it will be understood 25 that I do not wish to be limited to one form, inasmuch as variations within the scope of the claims and the spirit of the invention which may be suggested from the disclosure to those versed in the art are contemplated.

30 What I claim as new and desire to secure by Letters Patent of the United States is:—

1. In a light projector comprising a casing, a reflector and a light source located 35 in the focal region of said reflector, means for adjustably securing said light source to said casing, said means comprising a collet and a shaft extending through said collet, said collet operating as a bearing to 40 permit the shaft under certain conditions to be rotated about its longitudinal axis and to be slid in the collet along the length of said axis, and clamping means for operating the collet to clamp the shaft to said 45 collet and for clamping the collet to the casing, said means comprising a ball and socket device in operative engagement with the casing, a head for the collet at one end and a nut in operative engagement with the collet beyond said head, said ball and socket being located between said nut and head 50 for clamping the shaft to the collet and the collet to the casing.

2. In a light projector comprising a casing, a reflector and a light source located 55 in the focal region of said reflector, means for adjustably securing said light source to said casing, said means comprising a collet and a shaft extending through said collet, said collet operating as a bearing to 60 permit the shaft under certain conditions to be rotated about its longitudinal axis and to be slid in the collet along the length of said axis, and clamping means 65 for operating the collet to clamp the shaft

to said collet and for clamping the collet to the casing, said means comprising a ball and socket device in operative engagement with the casing, said collet extending through said ball, socket and casing, a head 70 for said collet on one side of said ball and socket elements, a nut in threaded engagement with the collet on the other side of said elements for drawing said ball and socket into operative engagement with said casing. 75

3. In a light projector comprising a casing and a light source, supporting means for said source comprising a spherical section in said casing, a ball on one side of said section and a socket on the opposite side thereof, and means for clamping said spherical section between said ball and socket, said means comprising a collet extending through said ball, socket and spherical section, said collet having a head at one end and a nut at the other, said ball and socket being located between said head and nut and adapted to be clamped together therebetween when said nut is turned, and a shaft extending through said collet with one end outside of the casing and with one end inside of the casing, and a light source mounted on said shaft inside the casing, said shaft being adapted to be clamped to said collet when said nut is turned to clamp said ball and socket. 90

4. In a light projector comprising a casing, a reflector and a light source located 100 in the focal region of said reflector, means for adjustably securing said light source to said casing, said means comprising a collet and a shaft extending through said collet, said collet operating as a bearing to permit the shaft under certain conditions to be rotated about its longitudinal axis and to be slid in the collet along the length of said axis, and clamping means for operating the collet to clamp the shaft to said collet and for clamping the collet to the casing, said 105 clamping means comprising a member having a tapered opening through which said collet passes and means for causing engagement of said collet by said member. 110

5. The combination with a casing having an opening, of means for adjustably mounting a lamp on the casing comprising a shaft which projects through said opening for supporting the lamp, a sleeve on the shaft which forms a bearing for the shaft, said sleeve projecting through said opening and being provided with threads at its outer end, walls surrounding the sleeve on opposite sides of the casing and between which the casing is clamped, means carried by one of said walls for effecting clamping of the inner end of said sleeve on the shaft, and a nut on the threaded end of the sleeve for clamping said walls against the casing and the sleeve on the shaft. 115

6. The combination with a casing having a spherical section provided with an opening, of means for adjustably mounting a lamp on the casing, comprising a shaft 5 which projects through said opening for supporting the lamp, a sleeve on the shaft which forms a bearing for the shaft, said sleeve projecting through said opening and being provided with threads at its outer 10 end, walls of spherical section surrounding the sleeve on opposite sides of the spherical section of the casing and between which such portion of the casing is clamped, means carried by one of said walls for effecting 15 clamping of the inner end of said sleeve on the shaft, and a nut on the threaded end of the sleeve for clamping said walls against the casing and the sleeve on the shaft.

In witness whereof, I have hereunto set 20 my hand this ninth day of July, 1929.

ROY B. MINER.
